UNITED STATES PATENT OFFICE.

FREDERICK E. KEY, OF ST. LOUIS, MISSOURI.

BOILER.

1,409,345.

Specification of Letters Patent. Patented Mar. 14, 1922.

Application filed April 12, 1919. Serial No. 289,754.

To all whom it may concern:

Be it known that I, FREDERICK E. KEY, a citizen of the United States of America, a resident of the city of St. Louis, in the 5 State of Missouri, have invented certain new and useful Improvements in Boilers, of which the following is a full, clear, and exact description, reference being had to the accompanying drawings, forming a part of 10 this specification.

My invention relates to improvements in boilers, and all of the features of the invention herein disclosed may be used in water-tube boilers, i. e., boilers provided with tubes 15 for the circulation of water or other liquid. One of the objects of the invention is to provide an improved means for separating the water from the rising steam bubbles, permitting the relatively cool water to return 20 freely to a lower level. Prior to this invention, water tube boilers have been provided with upwardly inclined tubes for the rising streams of hot water and steam, and all of the rising water is usually carried with the 25 steam to the upper portion of the boiler where the steam passes from the surface of the cooler water while the latter is permitted to return from the top to the bottom of the boiler.

In the preferred form of my invention, all 30 of the steam bubbles and some of the hot water are permitted to rise to the upper portion of the boiler, but a very large proportion of the water is permitted to pass from the steam and return freely at various elevations without rising to the upper portion 35 of the boiler. More specifically stated, the boiler I have shown to illustrate the invention is provided with headers which are connected together by inclined tubes wherein streams of water and steam are conducted 40 upwardly and discharged into one of the headers. From the last mentioned header, all of the steam rises to the top of the boiler, 45 but water has an opportunity to return freely from the last mentioned header without rising to the top with the steam. To accomplish this, the headers are also connected together by relatively cool return tubes which 50 are preferably located at various elevations so as to permit the relatively cool water to pass quickly from the rising steam. In the boiler hereinafter described, the headers are connected by two groups of relatively cool 55 return tubes located on opposite sides of a

middle group of tubes wherein the steam and hot water rises from one header to the other. All of these tubes are inclined so that the streams of hot water and steam will rise in the middle group of tubes while the streams 60 of relatively cool water will flow downwardly in the side groups of return tubes. The streams of hot water and steam therefore flow upwardly at the hot middle portion of the boiler while the relatively cool 65 water flows downwardly in the inclined return tubes at opposite sides of the boiler. The relatively cool water is thus conducted from the steam in one of the headers, and permitted to return in streams at various 70 elevations, instead of being forced to the top with the steam. Another object of the invention is to provide an improved down-draft boiler.

With the foregoing and other objects in 75 view, the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claim hereunto appended.

Fig. I is a front elevation, partly in section, illustrating a downdraft boiler constructed in accordance with the invention.

Fig. II is a side elevation with a portion of the side wall broken away to show the 90 return tubes.

Fig. III is a vertical section taken approximately through the center of the boiler.

The furnace herein shown comprises a suitable foundation 1 which supports side 95 walls 2 and a rear wall 3. The front wall is formed by two pairs of double doors (Fig. I), each pair consisting of a door 4 supported by hinges 5 and a door 6 connected by means of hinges 7 to the door 4. The free edge of each door 6 is cut away to receive a door frame 8 and a steam pipe 9. The top wall 11 is formed with horizontal portions (Fig. I) at opposite sides of a central flaring outlet device 12 through 100 which the smoke is discharged from the furnace.

The boiler comprises a front header 13, a rear header 14 and numerous tubes connecting said headers. The rear header 14 110

is preferably lower than the front header, and the tubes are preferably inclined upwardly from the rear to the front header. At the middle of the boiler, I have shown a 5 middle group of steam and water conducting tubes 15 arranged to form two inclined rows of tubes (Fig. I) converging toward their lower ends, so as to provide an upper grate approximately V-shaped in cross section. In 10 a grate of this kind it is desirable to separate the tubes as far as possible to provide free outlets for the flame and combustible gases passing downwardly from the fuel, but the fuel must not drop too freely between the 15 separated grate tubes. Attention is therefore directed to the advantages of the V-shaped grate formed by the inclined rows of tubes 15. These tubes are widely separated to permit the free escape of flame and gases, 20 but they are well adapted to support the fuel. At any point above the V-shaped grate, the fuel lies directly above a tube 15, and the fuel will not drop too freely between the tubes. The middle group of tubes 25 may also include a horizontal row of tubes 15^A (Fig. I) above the grate and vertical rows 15^B at the sides of the grate.

Intermediate groups of water tubes 16 are located on opposite sides of the middle 30 group of tubes, and vertical partition walls or deflectors 17 are interposed between the middle group and the intermediate groups. A cover plate 18 is secured on the deflectors 17 and arranged over the V-shaped grate to 35 form the top wall of the fuel chamber. Groups of return tubes 19 (Figs. I and II) are disposed on opposite sides of the intermediate groups 16, and partitions 20 are located between the tubes 19 and 16. As 40 will be hereinafter described, the partitions 20 shield the return tubes 19 from the heating medium at the tubes 16, and to avoid undue loss of heat, insulating walls 21 are interposed between the partitions 20 and the 45 side walls 2.

To provide for the delivery of fuel to the V-shaped grate formed by tubes 16, the front header 13 has an opening 21' (Fig. III) normally closed by a door 22 (Figs. I 50 and III) on the door frame 8, and this door has a draft inlet 23 for the admission of air to the bed of fuel. A lower grate 24 is located directly below the grate formed by tubes 16. An ash pit 25 is formed below the lower grate 24. A door 25' (Figs. I and III) at the front of the ash pit is provided with inlet openings 26 for the admission of air below the grate 24. 27 designates a door arranged in front of grate 24 and having a draft inlet 28.

When the boiler is in service, fresh coal is fed to the upper grate and as it becomes partially consumed some of this solid fuel drops onto the lower grate 24 where the combustion is completed. The draft is down-

ward through the upper grate and upward through the lower, as indicated by arrows in Fig. I. The combustible gases passing downwardly through the fuel on the upper grate are permitted to escape freely between the 70 widely separated tubes 15, and they are burned in the space below where they meet the hot air and products of combustion rising from the lower grate. The flame and hot gases passing from the upper grate are 75 deflected downwardly and under the vertical deflectors 17, and thence upwardly across the tubes 16.

The middle and intermediate groups of tubes 15 and 16 are exposed directly to the 80 heating medium so as to create a circulation whereby steam and hot water are discharged from the upper ends of these hot tubes and into the front header 13. Rising streams of steam and hot water are thus discharged 85 into the header 13 with the result of raising the water in said header and causing some of the water to return in the usual manner, by passing through tubes 29 near the top of the boiler.

A partition 30 (Figs. I and III) is secured in the upper portion of header 13 to form a steam chamber 31 above the upper ends of the water-conducting tubes, and a group of superheating tubes 32 connects this steam 95 chamber to the upper portion of header 14. All of the tubes herein shown may be inclined upwardly from the rear to the front header, and they may be parallel with each other as shown by Figs II and III. Each 100 tube is in free communication with both headers, and plugs 33 are secured in the headers at points opposite the ends of the tubes. 34 designates a drain pipe leading from the lower end of header 14.

The top wall or cover 18, arranged over the V-shaped grate, is provided with a vent opening which is normally closed by a sliding door 35 to which an operating rod 36 is secured. The headers are reinforced by hollow staybolts 37, and the rod 36 passes through one of these staybolts.

To enable the fireman to most effectively stir the bed of fuel on the V-shaped grate, a poker-receiving opening 38 is formed in 115 the door frame 8 and header 13 at a point opposite the narrow lower end of the V, and this opening is normally closed by a door 39.

The steam bubbles rising with the water pass into the front header 13 as previously 120 pointed out, and all of the steam passes through pipes 29, near the top of the boiler, to the header 14 and then back through the superheating tubes 32 to the steam chamber 31 above the partition 30. It will be noted that the partition 30 prevents the steam from passing directly to the steam chamber 31, and that all of the steam must pass through the superheating tubes 32 before reaching the chamber 31.

Attention is now directed to the return tubes 19 located at opposite sides of the boiler for the purpose of freely and quickly returning relatively cool water from the 5 header 13 to the header 14. Water and steam rise in the hot tubes 15 and 16 as indicated by arrows in Fig. III, and relatively cool water alone flows downwardly in return tubes 19, as indicated in Fig. II. To insure 10 the desired circulation in these return tubes, they are shielded by means of the partitions 20 which separate them from the heating medium at the tubes 16. The return tubes 19 are relatively cool so as to cause the water 15 therein to flow downwardly to the header 14, thereby creating a rapid circulation at opposite sides of the boiler. I preferably employ a number of the cool return tubes 19 and arrange them at various elevations, so 20 that the relatively cool water in header 13 can escape freely from the steam at different elevations and return through the various tubes 19, instead of rising to the top of the boiler with the hot steam. Owing to the 25 peculiar manner in which the water is circulated, the steam can rise quickly to the surface without forcing a large body of water to the top of the boiler, and most of the water flowing into the manifold 13 is 30 quickly returned through the tubes 19 to the lower manifold 14, from which it again rises through the hot tubes 15 and 16. The many advantages of this rapid circulation and the quick separation of relatively cool 35 water from the rising steam bubbles will be readily understood by those skilled in this art.

headers one of which is provided with an 40 opening for the admission of fuel, a middle group of steam and water receiving tubes connecting said headers to form a grate for the fuel, intermediate groups of steam and water receiving tubes connecting said headers and disposed on opposite sides of said middle group, groups of return tubes connecting said headers and disposed on opposite sides of said intermediate groups of steam and water receiving tubes, partition 45 members arranged between said return tubes and the intermediate groups of tubes so as to shield the return tubes from the heating medium at the intermediate groups, all of said tubes being inclined upwardly from one 50 header to the other and the ends of said tubes being in direct communication with the headers, said middle and intermediate groups of tubes being exposed directly to the heating medium so as to discharge rising streams 55 of steam and hot water into the header at their upper ends, and the return tubes being relatively cool so as to conduct the relatively cool water downwardly and into the header 60 at their lower ends, the tubes in each group 65 being approximately parallel with the tubes in the other groups, a partition arranged in the header to which the relatively high ends of the inclined tubes are secured so as to form a steam chamber above said ends, and 70 a group of superheating tubes located above said intermediate groups and connecting said steam chamber to the upper portion of the header at the lower ends of the tubes.

In testimony that I claim the foregoing 75 I hereunto affix my signature.

FREDERICK E. KEY.
